UNITED STATES PATENT OFFICE.

CONSTANTIN DUDA, OF CHICAGO, ILLINOIS.

FLOOR-SCRAPER.

No. 830,651.

Specification of Letters Patent.

Patented Sept. 11, 1906.

Application filed March 21, 1906. Serial No. 307,199.

To all whom it may concern:

Be it known that I, CONSTANTIN DUDA, a citizen of the United States, residing at Chicago, in the county of Cook and State of Illinois, have invented new and useful Improvements in Floor-Scrapers, of which the following is a specification.

This invention is a tool or device for planing or scraping down floors or other uneven surfaces, especially by hand.

The principal features of this device are a block provided with a long handle, a weight, and a scraper-blade which is adjustable in the block.

15 In the drawings, Figure 1 is a side view of the device. Fig. 2 is a vertical longitudinal section of the same. Fig. 3 is a front view.

Referring particularly to the drawings, 10 indicates a block having an aperture 10^a, which is adapted to receive a removable weight 11. At the rear end of the block 10 there is a handle 12, which is attached in an inclined recess or socket 13 by means of a bolt 14. The handle 12 may be provided 25 with an ordinary plane-grip, or the long handle may be omitted and the block itself provided with the grip for bench or close work.

The rear end of the scraper-block is mounted upon wheels 15 at each side. At the front 30 end the block is an inclined or sloping face 16, which receives the scraper bit or blade 17, held in place by a lever-plate 18, having a shoulder 18^a, resting upon a cross-rod 19, extending between the cheeks 16^a at the head 35 of the block.

20 is an adjusting and clamping screw which bears at its foot against the blade and causes the lower end of the plate 18 to clamp the edge of the blade.

40 21 is a guide or face piece through which the cutting edge of the scraper-blade passes or

projects. This face-piece is attached to the cheeks of the head 16 by means of pivot-pins 21^a, so as to allow the face-piece to rock and follow the contour of the surface which is being scraped on account of its being pivoted on its bearings 21^a. The face-piece slides upon the work and governs the cut of the blade, which may be adjusted as desired by loosening the clamp.

45 In the use of the device the block is pulled or drawn toward the operator and over the surface of the work by means of the handle, and the blade scrapes the floor or other work.

50 I claim—

1. A plane comprising a block mounted on wheels at one end and having at the other end a pivoted face-plate for contact with the work, and a blade secured at the front end of the block and projecting through said plate. 55

2. A plane comprising a block having a handle projecting at the rear end and wheels upon which the block is carried at said end, a weight on the block, a face-plate at the front end of the block, for contact with the work, and a blade secured to the front end of the block and extending through said face-plate. 65

3. A plane comprising a block mounted on wheels at its rear end and having projecting cheeks at each side at its front end, a face-plate pivoted between the cheeks at the bottom thereof, to contact with the work, and a blade clamped to the front end of the block, between the cheeks, and projecting at its lower edge through the face-plate. 70

75 In testimony whereof I have signed my name to this specification in the presence of two subscribing witnesses.

CONSTANTIN DUDA.
